SAFETY LADDER STEP

Howard W. Ronfeldt, Toledo, Ohio, assignor to
Ronfeldt Associates, Inc., Toledo, Ohio, a cor-
poration of Ohio

Application September 12, 1947, Serial No. 141,342

Term of patent 14 years

(Cl. D15—8)

To all whom it may concern:

Be it known that I, Howard W. Ronfeldt, a citizen of the United States and a resident of Toledo, Lucas County, Ohio, have invented a new, original, and ornamental Design for a Safety Ladder Step, of which the following is a specification, reference being had to the accompanying drawing, forming a part thereof.

In the drawing:

Figure 1 is a top view of the safety ladder step, showing my new design;

Figure 2 is a front end elevational view of the safety ladder step;

Figure 3 is a rear end elevational view of the safety ladder step; and

Figure 4 is a side elevational view of the safety ladder step.

I claim:

The ornamental design for a safety ladder step, as shown.

HOWARD W. RONFELDT.
